UNITED STATES PATENT OFFICE.

LAMONT W. ESTES, OF SACRAMENTO, CALIFORNIA.

SPIKE-MAKING MACHINE.

SPECIFICATION forming part of Letters Patent No. 430,603, dated June 17, 1890.

Application filed February 18, 1890. Serial No. 340,930. (No model.)

To all whom it may concern:

Be it known that I, LAMONT W. ESTES, a citizen of the United States, residing at Sacramento, Sacramento county, State of California, have invented an Improvement in Spike-Making Machines; and I hereby declare the following to be a full, clear, and exact description of the same.

My invention relates to the class of machines for making spikes.

It consists in the novel constructions, combinations, and arrangements hereinafter fully described, and specifically pointed out in the claims.

15 The object of my invention is to provide a simple and effective machine for beveling or tapering the ends of the spikes, and cutting each spike off from the bar as it is fed into the machine.

20 Referring to the accompanying drawings for a more complete explanation of my invention, Figure 1 is a plan of my machine. Fig. 2 is a front elevation of the same. Fig. 3 is an elevation taken from the left-hand side of Fig. 1. Fig. 4 is an elevation from the right-hand side. Fig. 5 is a view showing a modification of the eccentrics and of the means for operating the eccentric shafts. Fig. 6 is a detail of the eccentrics and intervening 25 cutter.

30 A is a frame of suitable description, having at one end a power-shaft B, in which is a crank b, which operates a plunger C, these parts being essentially the same as those of a well-known form of bolt-heading machine, the plunger being used to upset the head of the bolt, and in my machine being used to 35 form the head of the spike.

35 On the front of the machine is a rocking 40 block D, which has fitted in its inner end the main jaw d. Opposing these parts is a fixed block E, having fitted to it the main jaw e. These two jaws form the clamps for holding the bar introduced between them.

45 The rocking block D, as shown in Fig. 2, is fulcrumed below at the point d', and said block projects out to the side of the machine, and has connected with it, by the pin d², the pivoted operating-lever F, the rear end of 50 which carries an anti-friction roller f, upon which operates a cam G, the particular shape of which is shown in Fig. 3, the said cam be-

ing upon the power-shaft B. This cam moves the lever, which in turn rocks the block D, thereby causing its jaw d to move through an 55 arc of a circle, at the lower portion of which it is adapted to bind tightly upon the inserted bar, and as it rises again, which it does by the weight of the other end of its block, it relieves said bar.

60 The operation of the parts as far as described is as follows: The bar, which is represented by X, is introduced into its place alongside of the fixed jaw, and then the rocking jaw comes down on its other side and 65 firmly binds it between itself and the fixed jaw. Then the plunger comes up and forms the head of the spike. In front of these jaws are supplemental jaws, the movable one being 70 designated as H, as seen in Fig. 1. It is pivoted at h, and is operated by means of a connecting-link h', which is joined to a pivoted bell-crank lever or arms h², operated by a connecting-rod h³, the rear end of which is provided with a strap h⁴, encircling an eccentric or 75 cam h⁵ on the drive-shaft. The stationary supplemental jaw is represented by I, and is opposite to the movable jaw H and in the same horizontal plane. These two jaws are adapted to bind upon the projecting end of 80 the bar X, so as to form a suitable resistance for the operation of the cutter. This cutter (designated by J) is a sliding bar, Figs. 1 and 85 6, passing through the stationary block E, and adapted to be forced against the projecting end of the bar X, just in front of where the secondary jaws clamp it. This cutter is operated by a pivoted lever j, the rear end of which is provided with an anti-friction roller j', operated by a side cam j² on the power- 90 shaft B.

95 The operation, taken up from the point at which it was left, is as follows: The movable supplemental jaw H presses the bar X between itself and the stationary supplemental 100 jaw I, and, holding it tightly, said bar X receives the stroke of the cutter J, and is thereby cut off into a suitable spike length. Now, in order to form the beveled or tapering point of the spike, I have the following construction: Seated in the front of the machine on one side is an upper rock-shaft K, which carries on its inner end an eccentric k, which lies just above the outer end of the bar X.

L is a second rock-shaft in the same vertical plane as the first, but below it, said shaft carrying on its inner end an eccentric l, which is under the end of the bar X. These eccentrics are operated by means of crank-arms M on the shafts Fig. 4, with which are connected links m, the other ends of which are attached to a reciprocating carriage N. This carriage is projected forward by a cam O on the power-shaft, the shape of which is shown in Fig. 4, said cam acting against an anti-friction roller n on the carriage, and the carriage is withdrawn by means of a second anti-friction roller n', which operates within a cam-groove o on the inner side of the cam O. The effect of this construction is that the two eccentrics are brought down upon the end of the bar X and roll it into the beveled or tapering point of the spike. This operation necessarily takes place when the bar is free, as in the rolling the spike must be moved inwardly. Therefore when the eccentrics begin to operate on the spike the latter is relieved entirely of the main jaws and slips through the supplemental jaws, so that it can move inwardly under the rolling effect of the eccentrics, and by slipping through the supplemental jaws avoid finning.

The reason for leaving the bar X projected so far in front of the main jaws will now be seen, as said projecting end must be sufficiently long to provide for the rolling, and at the same time the backward action of the eccentrics in forming the tapering point of the spike and the necessity for the supplemental jaws will also be seen in that having the projecting end of the bar some provision must be made for the resistance to the stroke of the cutter in severing the bar into spike-lengths.

A feature of my machine will also be seen in the location and construction of the eccentrics and their shafts. By having the eccentrics just narrow enough to operate upon the bar, and mounting said eccentrics upon shafts of smaller diameter, I am enabled to leave a space between said shafts for the seating both of the stationary supplemental jaw and the reciprocating cutter-bar. This position of the cutter-bar is clearly shown in Figs. 2 and 6, and when the eccentrics are turned out of contact with the bar and are in an inoperative position they are raised far enough to wholly relieve the bar and permit the proper action of the cutter upon it.

In Fig. 5 I have shown a modification with regard to the mechanism by which the eccentrics are operated, and also a modification in the shape of the eccentrics themselves. This latter feature consists simply in dispensing with the complete eccentric and substituting therefor segmental eccentrics, which serve the same purpose. Instead of the reciprocating carriage and intervening links and cranks by which the eccentrics are operated I may use, as is shown in

this figure, a gear-train represented generally by P.

Having thus described my invention, what I claim as new, and desire to secure by Letters Patent, is—

1. In a spike-making machine, the combination of opposing main jaws between which the inner end of the bar is held, supplemental jaws for holding its projecting outer end, and a reciprocating cutter independent of said jaws for severing the bar just beyond the supplemental jaws, substantially as herein described. 75

2. In a spike-making machine, the opposing main jaws, in combination with the stationary supplemental jaw, the movable supplemental jaw for holding the spike at its projecting end, the link, connecting-rod, intervening connections between said rod and link, and the eccentric or cam on the power-shaft for operating the movable supplemental jaw, and the reciprocating cutter for severing the bar near the supplemental jaws, 80 substantially as herein described. 85

3. In a spike-making machine, the combination of the main jaws for holding the bar at one end, the supplemental jaws for holding its projecting end, the independently-moving cutter for severing the bar near the supplemental jaws, and the means for operating the cutter, consisting of the pivoted lever and the cam on the power-shaft for operating said lever, substantially as herein 95 described. 100

4. In a spike-making machine, the combination of the rock-shafts, the eccentrics on their inner ends operating to roll the beveled or tapering point of the spike, and the reciprocating cutter between the rock-shafts, and adapted to sever the bar into spike-lengths, substantially as herein described. 105

5. In a spike-making machine, the combination of the main jaws for holding the bar at one end, the supplemental jaws for holding the projecting end of the bar, the reciprocating cutter for severing the bar near the supplemental jaws, the rock-shafts above and below the cutter and between which said cutter is seated, and the eccentrics on the rock-shafts for operating on the severed end of the bar to form the beveled or tapering end of the spike, substantially as herein described. 115

6. In a spike-making machine, the rock-shafts having on their inner ends the eccentrics for rolling the beveled or tapering point of the spike, in combination with the cranks of the rock-shafts, the links of the cranks, the reciprocating carriage with which the links are connected, and the cams on the power-shaft for reciprocating the carriage, substantially as herein described. 120 125

In witness whereof I have hereunto set my hand.
